TIPPING LOCK FOR A GARBAGE CHUTE

Johannes Petrus Hekelaar, The Hague, Netherlands, assignor, by mesne assignments, to N. V. Ontwerp- & Exploitatiebureau "Shunt," a limited liability company, The Hague, Netherlands

Application September 6, 1956, Serial No. 608,375

5 Claims. (Cl. 193—34)

This invention relates to a tipping lock for a garbage chute.

It is known to provide buildings divided into flats with a chute for the removal of garbage, which chute is connected to the various flats by means of closable apertures. On the means for closing said apertures high demands are made, the most important ones of which are:

- (a) A good sealing in order to prevent bad odours and bacteria from entering the flat from the chute;
- (b) The prevention of the chute being clogged up by too large pieces thrown into it;
- (c) The prevention of garbage sticking in the lock;
- (d) The ease of cleaning.

It is known to give said closure means the form of a tipping lock, the front wall of which is formed as a cover closing the mouth of the garbage chute. In the closed position the lock, therefore, is located in a branch of the chute. Upon being opened the lock tilts forward so that the garbage can be thrown into it, while when the lock is closed the garbage will drop therefrom into the chute. The disadvantage of this construction consists in that it is possible to throw through or past the lock too large and especially too long articles into the chute which may cause it to clog up, while in the opened position of the lock there is a direct communication between the flat and the chute, so that bad odours and bacteria are apt to enter the flat. The object of the invention is to obviate the said disadvantages.

The tipping lock according to the invention comprises a frame plate provided with an aperture and adapted to be fitted about the mouth of the garbage chute, to the lower edge of which aperture an open shaft and a bent plate, are hingedly mounted. If the chute is closed the shaft is located behind the frame plate and then has a substantially vertical position. The hinged connection with the frame plate is located at its foremost lower edge. The bent plate is hingedly connected with the frame plate at the bend or in the immediate vicinity thereof. The foremost portion of said plate serves as a cover for the aperture in the frame plate and its rearmost portion serves as a bottom for the shaft. In its closed position the cover is entirely or substantially vertical. The angle between the foremost and the rearmost portion of said bent plate is larger than the angle between the lower edge and the front wall of the shaft.

If the shaft is in its vertical position it rests with an edge arranged about its front wall in a rabbet of the frame plate. If the cover is likewise closed, the bottom plate does not bear against the lower edge of the shaft, so that articles deposited in the shaft may drop from the shaft and in doing so they will be guided into the chute by the inclined bottom plate.

Seeing that in said position both the front wall of the shaft and the cover bear against the frame plate there is a double closure of the chute, which is particularly favourable from a hygienic point of view.

When the cover is turned downwards the bottom plate

will move upwards, will lie against the lower edge of the shaft and will take said shaft along during the further downward movement of the cover, so that the shaft will tilt forward. A stop or like member limits the movement of the lock. The extreme position is the one in which the opening of the lock is located substantially beyond the frame plate. The shape of the shaft preferably is such that its rearmost upper edge is in the immediate vicinity of the upper edge of the aperture in the frame plate then, while also the width of the shaft is such that it fits the aperture in the frame plate with relatively little play. Thus long articles that are too large to be thrown into the lock are prevented from being inserted into the chute past the shaft, which might lead to the chute being clogged up.

Preferably the bottom plate and the shaft are provided with locking means such that they are locked to each other in the non-closed position of the tipping lock. This renders it impossible to intentionally insert long articles through the lock into the chute, while at the same time gases from the chute are prevented from entering the flat.

It is advantageous to so construct the means limiting the extent to which the lock can be opened that, if desired, they can be rendered inoperative so that it is possible to tilt the lock entirely forward from the branch of the chute for cleaning purposes.

The invention will be illustrated with reference to the embodiment shown in the accompanying drawing. The figures diagrammatically show vertical sectional views of the same apparatus in various positions, i. e.:

Figure 1: lock closed.

Figure 2: cover partially open, bottom plate in contact with the shaft which still is in the vertical position.

Figure 3: the cover is opened slightly farther, the shaft has been tilted a little, the bottom plate is locked to the shaft.

Figure 4: the shaft is in the position for receiving the garbage.

Figure 5: the shaft is tilted entirely forward for cleaning purposes.

In the drawing the reference numeral 1 designates the garbage chute which by means of a branch 2 is connected to a flat. The mouth of the branch is provided with a frame plate 3, provided with an aperture 23. To the edge of said aperture a bent plate 4, 5 and a shaft 9 are secured by hinge means 7.

The frame plate is provided with a double rabbet 8 in which the outer edge 12 of the front wall of the shaft and the plate 4 can be accommodated, so that in the closed position of the tipping lock shown in Figure 1 a particularly tight obturation is obtained. A knob 6 facilitates the opening of the cover 4. As appears from Figure 1 the angle between the portions 4 and 5 of the plate is considerably larger than the angle between the lower edge 10 of the shaft and its front wall 12. In said position, therefore, the shaft 9 is open at its lower side and garbage, if any, may drop from the lock into the chute and during its fall it is guided towards the chute by the inclined bottom plate 5.

At the outside of a side wall of the shaft 9 a latch 14 pivotable about a pin 17 is provided, while the cover plate is provided with a projection 16 adapted to be engaged by the claw 15 of the latch. However, in the vertical position of the shaft an extension 18 of said latch bears against a stop 13 provided on the inside of the frame plate, so that said latch is in a lifted position and therefore is inoperative. At the same time the shaft is provided on its outside with a latch 20 pivotable about the pivot 19, which latch during the opening of the lock will at a given moment contact the stop 13 and thus pre-

vent the lock from being opened farther. If it is desired to tilt the lock still farther e. g. for cleaning purposes the latch 20 must be lifted after the lock has been normally opened, whereupon the lock can be tilted farther forward.

The figures show the tipping lock in various successive positions.

In Figure 1 the lock is closed. The front plate 4 bears in a rabbet 8 of the frame plate 3 and is kept in its closed position by a weight 22 secured to the bottom plate 5. The shaft 9 likewise bears in a rabbet of the frame plate with an edge provided on its front wall. In said position of the shaft a latch 14 pivoted to a side wall of said shaft bears with its extension 18 against a stop 13 provided on the inside of the frame plate, so that the end of the latch provided with the claw 15 is in a slightly lifted position. For opening the lock the front plate 4 is lowered by means of a knob 6. The bottom plate 5 formed integral with said front plate is raised then and at a given moment it comes into contact with the lower edge of the shaft 9, as shown in Figure 2. During a further movement of the front plate the bottom plate 5 will take along the shaft, so that said shaft will start tilting forward. A slight movement of said shaft is sufficient to release the latch 14 so that with its claw 15 it will engage a projection 16 provided on the side edge of the bottom plate 5. As a result the shaft and the bottom plate are locked to each other. A still further movement of the front plate causes the shaft to tilt forward until the latch 20 likewise pivoted to a side wall of the shaft engages the stop 13 and thus prevents the lock from being opened farther. Said position is shown in Figure 4. The mouth of the shaft is now entirely located outside the frame plate, so that garbage can easily be deposited in the shaft, whereupon the tipping lock is closed. During said closing movement the lock successively passes through the positions shown in Figures 4, 3, 2 and 1.

If it is desired to tilt the tipping lock still farther forward, e. g. for cleaning purposes the foremost end of the latch 20 should be forced downwardly when the shaft is in the position shown in Figure 4, so that the claw 21 of the latch is lifted and a further movement of the lock is rendered possible. A tipping lock tilted forward for cleaning purposes is shown in Figure 5.

It will be understood that the description of the tipping

lock given hereinbefore is only meant to elucidate the invention with reference to an embodiment. Other embodiments are possible without departing from the scope of this invention.

5 I claim:

1. A tipping lock for a garbage chute comprising an apertured frame plate adapted to be fitted about the tipping aperture of said lock, in which frame plate movable parts are hingedly mounted in the immediate vicinity of the lower edge of the aperture in said frame plate, characterized in that said movable parts comprise a shaft and a bent plate, whose foremost portion is formed as a cover for the aperture in the frame plate and whose rearmost portion serves as a bottom for said shaft, the pivot of the shaft being located adjacent its foremost lower edge and the pivot of said plate being located adjacent its bend, the angle between the foremost and the rearmost portion of said plate being larger than the angle between the lower edge and the front wall of the shaft, the arrangement being such that when the cover is tilted forward the bottom will lie against the lower edge of the shaft and will take the shaft along.

2. An arrangement according to claim 1, characterized in that the shaft and the bottom plate are provided with cooperating locking means so that in the non-closed position of the tipping lock the bottom plate is locked to the shaft.

3. An arrangement according to claim 2, characterized in that said locking means comprise a latch pivoted to the shaft, which latch is lifted in the closed position of the shaft by a stationary stop on the frame plate or on the wall of the chute, and a projection on the bottom plate adapted to be engaged by said latch when the shaft is tilted forward.

4. An arrangement according to claim 2, characterized by a stop which when the tipping lock is opened prevents said lock from being tilted to beyond the position in which the filling opening of the shaft is located entirely or substantially entirely beyond said frame plate.

5. An arrangement according to claim 4, characterized by means for rendering the stop inoperative, said means comprising a latch which in the open position of the lock runs against the stop, said latch being pivoted to the shaft and admitting of being lifted.
